UNITED STATES PATENT OFFICE.

WILLIAM E. SAYERS, OF NEW YORK, N. Y., ASSIGNOR TO THE HARTFORD CARPET COMPANY, OF HARTFORD, CONNECTICUT.

DESIGN FOR A CARPET.

SPECIFICATION forming part of Design No. 19,070, dated April 30, 1889.

Application filed March 7, 1889. Serial No. 302,331. Term of patent 3½ years.

To all whom it may concern:

Be it known that I, WILLIAM E. SAYERS, a citizen of the United States, residing in the city, county, and State of New York, have invented a new and original Design for Carpets, of which the following is a specification, reference being had to the accompanying photograph, which forms a part of the same.

The invention relates to a design to be worked into or upon surfaces, such as carpets or similar fabrics; and it consists in the novel configuration and grouping of figures herein specifically shown and claimed.

The accompanying photograph is a face view of a carpet showing my new design.

My design is composed of a body, A, and a border, B.

The body A is made up of diamond-shaped figures containing ornamentation of a varied character. Some irregular ornamentation is interspersed here and there between these diamond-shaped figures.

The border B has an inner portion made up of diamond-shaped figures similar to those of the body. The outer part consists of an irregular ornamentation having large alternating figures connected by an angular border-work, beyond which is a cloud-like ornamentation or effect.

What I claim as new, and desire to secure by Letters Patent, is—

1. The design for carpets, consisting of the body A, substantially as shown.
2. The design for carpets, consisting of the border B, substantially as shown.
3. The design for carpets, consisting of the body A and the border B, substantially as shown.

WILLIAM E. SAYERS.
